UNITED STATES PATENT OFFICE.

ERNEST C. REIMER, OF ALGONQUIN, ILLINOIS.

STEEL-WOOL HOLDER.

Application filed November 2, 1922. Serial No. 598,611.

To all whom it may concern:

Be it known that I, ERNEST C. REIMER, a citizen of the United States, residing at Algonquin, in the county of McHenry, State of Illinois, have invented a new and useful Steel-Wool Holder; and I do hereby declare the following to be a full, clear, and exact description of the invention, such as will enable others skilled in the art to which it appertains to make and use the same.

The invention relates to steel wool holders and has for its object to provide a device of this character comprising a metallic tubular member in which steel wool is disposed, and feed means whereby the steel wool may be forced towards the open end of the tubular member where it can be utilized for cleaning purposes; the holder forming means whereby the wool may be utilized without contact with the hand, and also forming means whereby pressure may be applied to the wool during a scouring operation.

A further object is to provide the device with a screw feed disc, which disc forces the steel wool outwardly.

A further object is to provide the steel wool with a paper wrapping whereby it may be easily handled and will easily feed downwardly through the device.

With the above and other object in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the holder.

Figure 2 is a vertical transverse sectional view through the holder.

Figure 3 is a horizontal sectional view through the holder taken on line 3—3 of Figure 2.

Referring to the drawing, the numeral 1 designates the casing of the holder, which casing may be of any suitable shape in horizontal cross section, however for purposes of illustration it is shown cylindrical shaped. Threaded on the upper end of the casing 1 is a cap 2, in a bearing 3 of which the feed screw 4 is rotatably mounted. The feed screw 4 extends axially into the casing 1 and

is imbedded at its lower end in the steel wool 5, which wool is adapted to be forced downwardly to the restricted open end 6 of the casing 1 where it can be used by the operator for scrubbing or cleaning, particularly pots and pans. The restricted opening prevents the steel wool 5 from dropping out of the casing 1, if the same should be loose therein, and at the same time causes the wool to be thoroughly compact where it leaves the tubular member 1, thereby allowing the maximum efficiency to be obtained from the steel wool when in use. When in use the operator grasps the tubular member 1 and rubs the exposed lower end 7 of the steel wool over a surface to be cleaned.

The steel wool 5 which is encased in paper 5^a is forced downwardly by the disc 8 which engages the upper end 9 thereof and through which disc the feed screw 4 is threaded at 10. Disc 8 is prevented from rotation during the rotation of the feed screw 4 by the guide rib 11 extending vertically and inwardly from the wall of the casing 1, which guide rib may be formed integrally with the inner periphery of the tubular casing as shown in Figures 2 and 3, or if so desired may be a separate strip brazed or otherwise secured to the tubular casing. Feed screw 4 is provided with an annular flange 12 which engages the under side of the cap 2 during the rotation of the feed screw thereby preventing upward movement of the feed screw and insuring downward feeding of the disc 8. The upper end of the feed screw 4 is provided with a ring 13 by means of which ring the device may be suspended from a support, however the ring also forms means adapted to be grasped by the operator for rotating the feed screw.

From the above it will be seen that a steel wool holder is provided, which holder is simple in construction, the parts reduced to a minimum and so constructed that the operator's hands will not come in contact with the steel wool during a scrubbing operation and also constructed in such a manner that the maximum pressure may be applied on the steel wool during a scrubbing operation.

The invention having been set forth what is claimed as new and useful is:—

A holder for paper cartons containing steel wool, said holder comprising a tubular member, a cap threaded on the upper end of the tubular member, a feed screw rotatably

mounted in a bearing of the cap, a carton
engaging disc threaded on the feed screw
and disposed within the tubular member, a
guide rib disposed within the tubular mem-
ber and engaging a recess in the disc, the
open end of the tubular member being con-
stricted.

In testimony whereof I have signed my
name to this specification in the presence of
two subscribing witnesses.

ERNEST C. REIMER.
